UNITED STATES PATENT OFFICE.

EPPA H. RYON, OF WORCESTER, MASSACHUSETTS, ASSIGNOR TO CROMPTON & KNOWLES
LOOM WORKS, A CORPORATION OF MASSACHUSETTS.

FILLING-DETECTOR MECHANISM FOR WEFT-REPLENISHING LOOMS.

939,954.

Specification of Letters Patent.

Patented Nov. 9, 1909.

Application filed February 4, 1909. Serial No. 476,067.

To all whom it may concern:

Be it known that I, EPPA H. RYON, a citizen of the United States, residing at Worcester, in the county of Worcester and State of Massachusetts, have invented certain new and useful Improvements in Filling-Detector Mechanism for Weft-Replenishing Looms, of which the following is a specification.

10 My invention relates to a filling detector mechanism for a weft replenishing loom, and particularly to a mechanical filling detector mechanism having a feeler, which is preferably located at the magazine end of the loom, and which is adapted to enter, through an opening in the shuttle box and the shuttle, to engage the filling on the bobbin in the active shuttle, as the lay moves forward, and on the substantial or practical 15 exhaustion of filling in the active shuttle, to operate mechanism connected with the weft replenishing mechanism, to cause a fresh bobbin to be supplied to the active shuttle in place of the substantially exhausted bobbin, 20 in the usual and well-known way.

The object of my invention is to improve upon the construction of a filling detector mechanism of the class referred to, and more particularly to provide a filling detector 25 mechanism having a feeler, which will feel for and detect the practical or substantial exhaustion of filling on the bobbin, without regard to the size of the bobbin on which the filling is wound, or the position of the 30 bobbin in the shuttle.

In my improvements I provide a spindle having a head adjustably fastened on said spindle, which is loosely held in a horizontally extending sleeve; said head is adapted 40 to yieldingly engage the filling on the bobbin as the lay beats up. A second head is loosely held in a recessed portion in the first mentioned head, and is also adapted to engage the filling on the bobbin. The second head 45 extends out of the first head, and in engaging the filling on the bobbin depresses the filling and causes the first mentioned head, by its engagement with the filling, to be held in its inoperative position, but when the filling 50 on the bobbin is practically or substantially exhausted, the few layers of the filling remaining on the bobbin will not be depressed sufficiently to prevent the longitudinally moving spindle from revolving, and

through this motion to put into operation 55 the mechanism which operates the weft replenishing mechanism, which may be of any ordinary construction.

My invention consists in certain novel features of construction of my improvements 60 which may be adapted to be applied to and used on any well known weft replenishing loom having a magazine for bobbins or filling carriers, said magazine being either stationary or movable.

I have only shown in the drawings a detached portion of a weft replenishing mechanism of a loom of the class referred to, with my improvements applied thereto, sufficient to enable those skilled in the art to understand the construction and operation thereof.

Referring to the drawings:—Figure 1 is a plan view of a detached portion of the end of a loom, and a portion of a shuttle, with my improvements applied thereto. Fig. 2 corresponds to Fig. 1, but shows some of the parts in a different position. Fig. 3 shows, on an enlarged scale, a central section through the feeler, on line 3, 3, Fig. 1, looking in the direction of arrow *a*, same 80 figure. Fig. 4 is an end view of the feeler, looking in the direction of arrow *b*, Fig. 3. Fig. 5 corresponds to Fig. 3, but shows some parts in a different position. Fig. 6 shows the end of the feeler, looking in the direction of arrow *c*, same figure. Fig. 7 is a portion of the feeler spindle, detached, looking in the direction of arrow *d*, Fig. 5. Fig. 8 is the spindle head, looking in the direction of arrow *e*, Fig. 7. Fig. 9 shows a modified 90 construction of the spindle head. Fig. 10 shows the spindle head, looking in the direction of arrow *f*, Fig. 9.

In the accompanying drawings, Figs. 1, and 2, 1 is a portion of the loom side or end 95 frame, 2 is the breast beam, on which is mounted in this instance a plate or stand 3, having the rearwardly extending arm 3', with two stands 4 thereon for the rotary feeler, to be hereinafter described.

5 is the shuttle, which carries a bobbin 6 having filling 7 thereon.

The mechanism which operates the weft replenishing mechanism, shown and described in my U. S. Letters Patent, No. 105 933,492, dated September 7, 1909, will be hereinafter described.

In the stands 4 on the arm 3' is in this

instance adjustably secured a bearing or support, shown in this instance in the shape of a tube 8; the outer end of the tube 8 is suitably covered and inclosed by a cap 8', see Figs. 3 and 5, and in the other end is a sleeve or cylindrical part 9, adapted to have a sliding motion within a hollow part of the tube 8. The sleeve 9 has an elongated slot or groove 9' therein, shown by dotted lines in Figs. 3 and 5, into which extends the inner end of a set screw 10 which extends through an opening in the tube 8. A rod or spindle 11 extends through the central hole in the sleeve 9, and through the cap cover 8' on the tube 8. One end of the spindle 11 has fastened thereon, by a set screw 12, the hub 13' of a hook lever 13. A helically coiled expansion spring 14 encircles the spindle 11, and bears at one end 20 against the cap 8', and at its other end against the sleeve 9, and acts to move the sleeve 9 with the spindle 11, toward the shuttle. The spindle 11 has a pin 11' thereon, which extends out from said spindle and into a curved or cam-shaped slot 9" in the sleeve 9. The inner end of the spindle 11 is screw threaded, and has adjustably secured thereon, by a nut 15, a head 16, which in this instance has its outer end toothed, as shown at 16', see Fig. 7, and adapted to engage the filling. Within the head 16 is a second head 18, which is loosely held within the head 16 by a pin 17 extending into an annular groove 18' in the head 18. The outer end of the head 18 bears against the pointed end 11" on the spindle 11. The head 18 has in this instance its outer end toothed, as shown at 18", and extends slightly beyond the head 16, to engage the filling 7 on the bobbin 6 when the bobbin has a sufficient supply of filling thereon, as shown in Figs. 1 and 3.

On the forward movement of the lay toward the spindle 11, the engaging end of the head 18 will form a slight depression in the filling on the bobbin, and the filling will engage the toothed portion 16' on the head 16, to prevent the spindle from revolving, and the pin 11' on the spindle 11, which extends into the curved or cam-shaped slot 9" in the sleeve 9, will move said sleeve, against the action of the spindle 11, see Fig. 3.

When the filling 7 on the bobbin 6 is practically or substantially exhausted, as shown in Figs. 2 and 5, the few layers of filling on the bobbin will not be depressed sufficiently to engage the toothed end 16' on the head 16, and as this head is free to move, the pin 11' on the spindle 11 will move in the curved or cam-shaped slot 9' in the sleeve 9, see Fig. 7, to cause the spindle 11 to rotate and raise the hook lever 13 into the path of, and to be engaged by the bar 19, as shown in Fig. 6, to 65 act as a stop for the operating lever shown

in Fig. 2, to put into operation the weft replenishing mechanism, through the mechanism shown in Figs. 1 and 2, and which corresponds to the mechanism shown and described in my said Letters Patent, No. 933,492. Said mechanism consists of a lever 20, to which the slide bar 19, having an elongated slot 19' therein, through which a guide pin 19" extends, is pivotally attached, and which has a stud 21 thereon which extends into an elongated opening 3" in the plate 3. A helically coiled contraction spring 22 is attached at one end to the stud 21, and at its other end to a stud 23 for an angle lever 24, which lever is loosely mounted on said stud 23, and has one arm made yoke-shaped, with an open end slot 24' therein, to receive the end 25' on a vertically extending rocking lever 25, having its hub 25" loosely mounted on the stud 26. The hub 25" has an extension 25'" thereon carrying a pin 27, on which is pivotally mounted the upper end 28 of a rod or connector to a cam lever, not shown, which is preferably operated by a cam, not shown, on the bottom shaft of the loom, not shown, to communicate a pivotal movement to the lever 24.

The angle lever 24 has a movement communicated to it, by the rock lever 25, at every other pick of the loom, said lever 24 has an elongated opening 24" therein, to receive a stud 29 on one end of a link 30; the other end of the link 30 is pivotally attached to a stud 31 on the arm 20.

The stud 21 has secured thereto one end of a curve shaped arm 35; the other end of said arm 35 is connected with a pin 36 on one arm of an angle lever 37, the hub 37' of which is pivotally mounted on a stud 38 on the loom side. The other arm of the angle lever 37 carries a stud 39, which is pivotally connected to the lower end of a link or connector 40; the upper end of said link or connector 40, not shown, is connected with the transerrer mechanism of the magazine.

All of the last above mentioned parts are of the same construction and operation as, shown in my said Letters Patent above referred to, and form no part of my present invention.

In Figs. 9 and 10 is shown a modified construction of the spindle head. In said figures, the pointed end 11" of the spindle engages the bobbin, and depresses the filling, and a series of needle points enter the filling when the bobbin has a sufficient supply of filling thereon. The needle points 20 are suitably secured to a conical shaped washer 21, by a ring 22. The washer 21 is adjustably fastened on the threaded end of the spindle 11 by a nut 15. When the filling on the bobbin is practically or substantially exhausted the needle points are not engaged by the filling and the spindle is allowed to rotate.

It will be understood that the details of construction of my improvements may be varied if desired.

Having thus described my invention, what I claim as new and desire to secure by Letters Patent is:—

1. In a filling detector mechanism, a rod or spindle, a sleeve having a cam slot and surrounding said rod or spindle, and movable therewith in one direction, a projection on said rod or spindle, extending into the cam slot in said sleeve, for the purpose stated.

2. In a filling detector mechanism, a rod or spindle having two heads attached thereto, one of said heads fixed to said rod, the other of said heads being free to revolve, and means to cause the coöperation of said heads with the filling in the shuttle.

3. In a filling detector mechanism, a rod or spindle having two adjacent heads attached thereto, one of said heads fixed to said spindle, the other of said heads being free to revolve, and means, including a shuttle and filling therein, to move said shaft longitudinally.

4. In a filling detector mechanism, a rod or spindle, means to support the same, a sleeve surrounding said spindle, and having a cam slot, and a longitudinal slot, a spring bearing against said sleeve, means, including a shuttle and filling therein, to operate said spindle, against the action of said spring, and to rotate said shaft when the filling has been practically exhausted.

5. In a filling detector mechanism, a rod or spindle having a central point, and a head on the end of said spindle having prongs or teeth surrounding said point, to coöperate with the filling on a cap or bobbin in a shuttle, and said shuttle, and means, including a cap or bobbin, to cause a partial rotation of said spindle when the filling on the cap or bobbin has been practically exhausted.

6. In a filling detector mechanism, a spindle adapted to have a longitudinal, and a rotary motion, devices at the end of said spindle to coöperate with the filling in the shuttle, and means, including a shuttle and filling therein, to reciprocate said spindle, and cause the same to partly revolve when the filling in said shuttle is practically exhausted.

7. In a filling detector mechanism, a reciprocating rod or spindle, having attached to one end thereof devices to coöperate with the filling in a shuttle, and the other end having a device attached thereto to coöperate with filling changing mechanism, and means, including a shuttle and filling therein, to move longitudinally said spindle, and to cause it to make a partial revolution when the filling has been practically exhausted.
